J. T. BRADLEY

NO CAPACITY CONTROL FOR CONDENSERS

Original Filed April 3, 1923

UNITED STATES PATENT OFFICE.

JOHN T. BRADLEY, OF TUTUILA, SAMOA.

NO-CAPACITY CONTROL FOR CONDENSERS.

Application filed April 3, 1923, Serial No. 629,737. Renewed February 25, 1925.

To all whom it may concern:

Be it known that I, JOHN T. BRADLEY, a citizen of the United States, residing at Tutuila, Samoa, have invented certain new and useful Improvements in No-Capacity Controls for Condensers, of which the following is a specification.

The invention relates to controlling means for variable condensers, such as are in common use in radio of the "vernier" type, wherein a large number of plates are adjusted for a coarse adjustment and a small number for a "vernier" adjustment. With apparatus of this nature a great difficulty has been found to be that the placing of the hand of the operator upon the knob of the dial for adjustment of the condenser introduces the capacity of the body into the circuit so that when the combined capacity of the condenser and body has been brought to the proper point the removal of the hand throws the tuning out.

An object of the present invention is the provision of means by which the condenser may be adjusted both as to coarse adjustment and as to fine adjustment without touching the knob of the dial and therefore without introduction of the objectionable capacity effect. A further object of the invention is the provision of means whereby a condenser may be adjusted by both movements with one hand and without change of the position of the hand, and therefore such that one condenser can be adjusted with each hand simultaneously. A further object of the invention is the provision of a "vernier" control susceptible of exceedingly fine adjustments.

Illustrative embodiments of the invention are shown in the accompanying drawing, wherein

Fig. 1 is a plan view;

Fig. 2 is a view similar to Fig. 1 with the top of the knob removed;

Fig. 3 is a detail section to an enlarged scale upon broken line 3, 3 of Fig. 1.

The "vernier" condensers of the type to which the present invention is applicable have their coarse adjustment controlled by a tube or sleeve, as 10, and their fine adjustment by a shaft 11 passing through the sleeve 10. Customarily, the dial 12 is secured to the sleeve 10 as by means of a set screw 13. By utilizing parts as shown in the drawing applicant is able to replace existing dials with the improved dial of the

invention. To apply the invention to dials for such replacement the knob 14 is made in two parts as shown, the part 15 being integral with the disk of the dial 12, and the set screw 13 being provided therein. To adjust the "vernier" parts by means of the shaft 11 the usual knob, which is applied to such shaft outside of the dial, as 12, is replaced by means of a worm wheel 16, which is provided with internal screw threads, and which may therefore be screwed upon the end of the shaft 11 in place of the usual knob referred to. In the event that the shaft 11 is found not to be threaded, the set screw 17 provided upon the up-standing flange 18 of the worm wheel 16 may be utilized to secure the wheel upon the shaft. If the shaft is screw threaded the set screw 17 acts as an additional securing means to prevent rotation of the wheel upon the screw thread.

To receive the worm wheel 16 a recess 19 is provided within the portion 15 of the knob 14. To cover the wheel a cap 20 having a recess 21 complementary to the recess 19 is provided, which cap has an additional smaller recess 22 for reception of the end of the shaft 11 and the flange 18. The cap 20 may be secured in place upon the portion 15 by means of screws 23.

To operate the worm wheel 16, a worm 24 is shown carried by a shaft 25 having a knob 26 at its extremity for grasp by the hand of the operator. An offset recess 27 is provided in each of the recesses 19 and 21 to accommodate the worm 24. To prevent longitudinal movement of the shaft 25 due to its action against the worm wheel, annular flanges or rings 28, 29 are provided rigid with the shaft 25, which rings engage semi-cylindrical grooves in the portions 15 and 20 of the knob 14. The grooves engaged by the rings 28, 29 are spaced from the recess, leaving a wall of material to receive the push of the rings.

With the parts assembled as illustrated, the knob 26 may be grasped by the hand of the user and the dial may be turned for coarse adjustment of the condenser by swinging the arm in the arc of a circle, as indicated by the arrow on Fig. 1. When the desired coarse adjustment has been secured a revolution of the shaft 25 may be caused by twirling the knob 26 by the fingers, which twirling may, if desired, cause a movement of 360° of the worm wheel 16

so as to quite certainly secure the best adjustment of the "vernier" portion of the condenser.

Minor changes may be made in the physical embodiment of the invention without departing from its spirit.

I claim:

1. A vernier condenser control comprising, in combination, means to move the condenser for coarse adjustment, means whereby said adjusting means by a second form of movement may control the vernier portion of the condenser.
2. A vernier condenser control comprising, in combination, a dial, means to move said dial for coarse adjustment of a condenser, means whereby said first named means by a different form of movement may control the vernier portion of the condenser.
3. A vernier condenser control comprising, in combination, a dial, a coarse adjustment condenser sleeve, a vernier shaft, means to secure said dial to the coarse adjustment sleeve, a shaft co-acting with said dial by bodily movement to cause revolution of the dial, means whereby said shaft by rotation about its axis may cause revolution of the vernier shaft of the condenser.
4. A vernier condenser control comprising, a dial, a knob upon said dial, means to secure said dial to the coarse adjustment sleeve of a condenser, a wheel adjacent said dial, means to secure said wheel to the vernier shaft of the condenser, means project-

ing from said wheel to cause revolution of 35 said vernier shaft, said last named means co-acting with the dial to cause revolution thereof by bodily motion about the axis of the shaft as a center for coarse adjustment of the condenser.

5. A vernier condenser control comprising, in combination, a dial, means to secure said dial to the coarse adjustment sleeve of the condenser, a worm wheel, means to secure the worm wheel to the vernier shaft of 45 the condenser, a shaft having a worm to co-act with said wheel, means to secure said shaft to said dial whereby movement of the worm shaft about the axis of the sleeve may cause revolution of the dial and sleeve, and 50 whereby revolution of the worm shaft upon its axis may cause revolution of the vernier shaft.

6. A vernier condenser control comprising, in combination, a dial having a recess, 55 means to secure said dial to the coarse adjustment sleeve of a condenser, a worm wheel seated in said recess, means to secure the worm wheel to the vernier shaft of the condenser, a worm shaft having its worm 60 seated in an offset of said recess and in mesh with said worm wheel, flanges on said worm shaft seated in separate recesses in said dial to prevent longitudinal movement of the worm shaft, a cover for said recess, said 65 cover having recesses complementary to the recesses of said dial.

JOHN T. BRADLEY.
